Design No. 549. —

Mangle and Phipps
Design for a Water Cooler
Patented 19th. April 1853. —

Fig 1

Fig. 2

11as-549

Edward M. Manaile, &
George Phipps, of Philadelphia, Pa.
Letters Patent No. 549 - Dated Apr. 19th 1853.

The schedule referred to in these Letters Patent and making part of the same

To all whom it may concern:

Be it known that we, Edwd M. Manaile and George Phipps, both of the County of Philadelphia, in the State of Pennsylvania, have invented or produced a new and original design to ornament a water cooler, we do hereby declare that the following is a full and exact description of the same.

Fig: 1. represents the front elevation of the Water Cooler complete. The base at letter a, begins with a square from which a series of points start up as at b, b, to a quarter bead C; thence a series of round and rays

2

Ms.

549

as at d, d, resting on an ovoli bed e e e e to the quarter bead f, thence a sixteensided column, which forms the body of the water cooler, at the joint of each of the faces a bead relieves the plain corners as at g, g, then the cap extends a little over (or eaves over the body) as represented at h, h, the extreme edge of the eave is a bead, next to the bead is an inclined plain as at i, from which raises an ovoli ornamented by a series of arrow heads looped together around the whole ovoli as shown at j, j, j, this completes the top of the body except the lid, represented by a birds eye at

Fig 2. The base of the lid is a bead as represented at k, k, from which a swelled plane is elevated a few degrees ornamented by a series of double balls and darts alternately as at l, l, l, against a bead m, from which an ovoli ornamented by a series of leaves as at n, n, the ovoli is surmounted by a slightly swelled plain raised $\frac{1}{16}$ of an inch above the ovoli which (plain) is ornamented by a series of balls and points as represented at o, o, and backed by a square from which a series of round ribs arise in a pyramidal ovoli form as at p, p, and then a square surface at the apex on which is designed to place the knob or handle of the lid.

We have thus described the several parts and ornaments but do not claim any of the separate ornaments, but

What we do claim as our invention and desire to secure by Letters Patent, is the design and configuration of the ornamental water cooler herein above described, and set forth in the accompanying drawings.
